J. S. JOHNSON ET AL

OIL INJECTOR

Filed Jan. 13, 1923

UNITED STATES PATENT OFFICE.

JOHN S. JOHNSON AND AUGUST JOHNSON, OF FARGO, NORTH DAKOTA.

OIL INJECTOR.

Application filed January 13, 1923. Serial No. 612,496.

Our invention relates to an oil injector or grease gun wherein it is desired to force oil or grease under pressure, either through a conduit to a joint or by direct connection at the discharge end of the grease gun.

Heretofore, various forms of grease injectors and pump oil cans have been made and these principally have been of a construction wherein the ejecting plunger or valves are immersed within the grease or oil, either in the bottom of the oil container or at one end. Our ejector differs from these oilers in that the ejecting cylinder and valve mechanism is a separable part and constitutes part of the cover of the container with all of the parts readily accessible for repair or adjustment.

Furthermore, the invention includes a simple form of handle which is provided and made up of a pair of levers, one of which is pivoted in a manner to coact with the operating plunger so that, when these handles are engaged by the operator, the oil can be pumped from the container with one hand very rapidly.

The oil injector is provided with a pair of check valves which are associated with the operating plunger so that one will release the oil out of the discharge end of the oil injector, while the other valve is positioned so as to hold the oil which has been drawn up from the well of the container and thus form a check valve so that the plunger will force the oil adjacent it out of the discharge end.

A feature of the invention resides in the positioning of these valves in relation to the ejecting plunger at the upper part of the oil container and the extending of the ejecting plunger cylinder across the oil container cover. This permits the oil ejector to be used much more easily than if the pump or plunger were immersed within the container.

The invention includes another feature which consists of means associated with the ejecting plunger whereby, as the oil is withdrawn from the reservoir chamber, air is drawn through the ejecting plunger in a manner to drain any oil, which may pass by the plunger end of the ejector, back into the oil reservoir. This construction eliminates the necessity of any packing gland and allows the ejecting plunger to be made

up so as to freely operate within its cylinder. In the drawings forming part of this specification:

Figure 1 is a side elevation particularly illustrated in cross section so as to disclose the operating mechanism of our invention.

Figure 2 is a plan view of the oil injector, a portion of the operating handles being broken away.

The drawings illustrate the oil injector A provided with an oil well or reservoir B which is adapted to contain fluid oil or soft grease oil. The ejecting mechanism C is positioned across the cover 10 for the chamber B.

The chamber B is made up in any suitable shape and may be cylindrical, as illustrated in the drawing, with a thin wall 11 and bottom end 12 so as to provide a suitable container for the oil.

The cover 10 is threaded at 13 to the wall 11 so that it can be removed when desired. This cover is provided with a cap or opening closure 14 which permits oil to be filled into the chamber B by removing this cap 14 and without making it necessary to remove the whole cover 10. The cap 14 is of ordinary well known construction being suitably threaded into the cover 10 and, if desired, a gasket placed beneath the same so as to make an air tight closure in the cover. All of this is of ordinary well known construction and is not illustrated in detail in the drawing.

The ejecting cylinder 15 of the ejecting mechanism C is formed as an integral part with the cover 10 and extends across the same so that, when the oil injector A is in upright position, the cylinder 15 extends horizontally across the top. Within the cylinder 15 is positioned the operating piston or plunger 16 which is held in outer position normally by the heavy duty coil spring 17. The coil spring 17 engages against the plunger end 18 of the piston and against the shoulder 19 formed in the cylinder. Extending through the shoulder 19 is an ejecting passageway 20 through which oil is ejected when the piston 16 is operated toward the same. On the discharge end of the passageway 20 a ball check valve 21 is positioned, which is held in position by the coil spring 22. The same is held in position by the nut 24 which is threaded into the

end of the piston 15. A suitable passageway 25 is formed in the nut 24 into which may be threaded the receiving end of a flexible conduit 27 so that oil can be discharged into the conduit and passed to the connection or be connected with a shackle bolt oiler in a manner to oil the joints of an automobile. Only a portion of the conduit 27 is illustrated and it is obvious that this can be of any suitable nature with the connections on the end of the same so that oil can be passed from the injector A to any point where it is desired for use.

The cylinder 15 is provided with a depending portion 28 in which is formed a chamber 29 for the check valve 30 which is normally held closed by a spring of any suitable type. A nut 31 holds the check valve 30 in position within the chamber 29 and is threaded to the member 28 so that the valve can be removed, if desired. A passageway 32 leads from the chamber 29 into the compartment in which the end of the plunger or piston 16 extends and in which the spring 17 is positioned.

Connected to the nut 31 in any suitable manner is the suction pipe 33 which extends to the bottom portion of the chamber B of the injector A. This pipe is provided with an ordinary screen 34 covering its lower intake end so as to filter the oil or grease drawn up through the pipe 33 by the action of the piston 16.

A pair of operating lever handles are provided and are removably connected by the lead engagement 35 to one end of the cylinder 15. One of the operating handles 36 is formed integral with the body portion 37 which is attached at 35 to the cylinder 15 so as to extend rigidly from the cylinder. The other handle of the pair 38 is pivoted at 39 between two spaced lugs as shown and is formed with a depending lug 40 which engages against the outer free end 41 of the piston or plunger 16. The heavy duty coil spring 17 holds the end 41 in engagement with the lug 40 at all times and normally forces the lug 40 against the lug 42 upon the integral operating handle when the piston is in outer position.

An annular recess or groove 43 is formed back of the plunger end 18 in the piston 16 which communicates with a passageway 44 leading into the chamber B of the injector, while a small hole or passageway 45 is formed in the piston connecting with the outer atmosphere and the annular recess 43 and the chamber formed thereby in the cylinder 15. By means of this construction, air is admitted through the passageways 45 and 44 into the compartment or reservoir B, as the oil or grease in the same is pumped or drawn out by the action of the piston 16. In this manner, any oil or grease which may pass beyond the plunger end of the piston

16 toward its outer free end 41 is drained and sucked back through the passageway 44 into the reservoir chamber B, thereby providing a means of preventing any leakage of oil at the outer free end of the piston 16. 70

In operation, our oil injector or grease discharger A is formed and adapted to operate to provide a high pressure injector. Due to the leverage of the operating handles 36 and 38 the plunger or piston 16 can be operated very rapidly so as to reciprocate back and forth within the cylinder 15 forcing the oil in front of the said piston valve 21 to the discharge end or conduit 27 on its forward stroke, drawing oil past valve 30 through the pipe 33 on its backward stroke so that the chamber in cylinder 15 wherein the heavy duty spring 17 is positioned is filled with oil or grease on the backward stroke of the piston. When the handles 36 and 38 are operated by squeezing them together, the piston forces the oil with a great deal of pressure owing to the leverage of the handles, and the heavy duty spring acts rapidly enough to bring the handles back 90 into open position ready to be operated again. In this manner, the injector A can be operated very rapidly with one hand. The handles 36 and 38 can be of any suitable length to provide the desired leverage. The check valve 21 prevents oil, even though it is ejecting out under pressure, from entering back into the chamber containing the spring 17 and the check valve 30 prevents the oil in the chamber containing the spring 17 from passing back into the reservoir B. 95

A very desirable feature of the invention resides in the simple, inexpensive construction with all of the parts accessible so that they can be replaced, repaired, or cleaned when desired. The arrangement of the parts and the positioning of the cylinder 15 permits a direct and easy use of the injector A so as to effectively pump oil or grease under high pressure to any desired point 110 where it is wanted for use.

The novel feature, admitting air to take the place of the grease withdrawn from the compartment B and to automatically draw any leakage past the operating end of the plunger back into the reservoir compartment is a very important feature of the invention. This construction permits the piston 16 to be so seated as to operate freely and thus the handles can be operated so rapidly as to reciprocate the piston back and forth much more easily than if it were necessary to make the piston tight with packing.

In accordance with the patent statutes, 125 we have described the principles of operation of our invention and have illustrated in the drawing a particular form for carrying out our invention, but we desire to have it understood that this is only illustrative 130

and that the invention can be carried out by other means and applied to other uses than that set forth within the scope of the following claims:

5 We claim:

1. An oil injector comprising an oil reservoir, a cylinder secured to said oil reservoir having a uniform bore throughout its length, check valved passages connecting said cylinder with the exterior and interior of said reservoir, a piston of a maximum diameter equal to the bore of said cylinder, normally extending outwardly beyond the same, said piston being formed with an annular passageway of a length substantially equal to the stroke of said piston, said passageway being at all times within the bore of said cylinder and a drainage port from said cylinder to said reservoir, communicating with said passageway.
2. An oil injector comprising a horizontally positioned cylinder, a hollow member screwable upon the end of said cylinder, said member being slotted at its upper end and formed with upwardly extending lugs, a handle extending outwardly from said

hollow member in the direction from said cylinder and integrally connected with said cylinder, a second handle pivoted to the upwardly extending lugs of said hollow member, a depending lug formed on said handle extending downwardly through the split portion of said hollow member and into the interior thereof, a piston within said cylinder adapted to extend into said hollow member and be engaged by said lug and operated therefrom.

3. A high pressure oil injector comprising a reservoir compartment, a removable cover for said compartment having an opening therein, a cylinder extending across and formed integral with said cover, a reciprocable plunger within said cylinder having an annular recess therein communicating at all times with said opening, said plunger also having a longitudinally extending air passage leading rearwardly from said recess to the open air, lever handles for operating said plunger and a check valved passage connecting said cylinder with said reservoir.

JOHN S. JOHNSON.
AUGUST JOHNSON.
